UNITED STATES PATENT OFFICE.

SALVADOR MONTES ALMENGLA, OF PITTSBURGH, PENNSYLVANIA.

ARMOR.

1,184,405.

Specification of Letters Patent.

Patented May 23, 1916.

Application filed January 11, 1916. Serial No. 71,414.

To all whom it may concern:

Be it known that I, SALVADOR MONTES ALMENGLA, a subject of the King of Spain, and residing in the city of Pittsburgh, in the county of Allegheny and State of Pennsylvania, have invented or discovered new and useful Improvements in Armor, of which the following is a specification.

My invention consists in certain new and useful improvements in resilient protective armor intended to present a yielding resistance to the impact of a projectile and to repel the same without penetration.

More particularly my invention relates to that form of resilient protective armor wherein the impact of the projectile is received on an outer skin or surface which is supported and spaced from the base by means of metallic springs. Armor of this general character has been designed wherein the outer skin or impact surface is in the form of a continuous, integral plate. Experiments, however, show that such an impact surface presents a relatively low resistance to penetration and tends to become bent, cracked or broken. Again, a flexible impact surface, composed of metal plates of relatively small area linked together at their edges and the individual plates spaced from the base by means of springs, has been proposed. In this case, it has been found that, while the plates successfully repel projectiles striking adjacent to the center of the plates, projectiles striking near the edges of the plates or at the juncture between plates tend to penetrate the armor.

My invention consists in improvements in the type of armor characterized by a flexible outer skin or impact surface, and I overcome the weakness above referred to by providing, in addition to the "primary" springs which support the bodies of the plates from the base, "secondary" springs which similarly support the abutting edges and corners of adjacent plates. With this novel provision, I have found that penetration is avoided and the projectiles are successfully thrown off without regard to their point of impact. Moreover, it has been found that where simple primary springs have been used to support the bodies of the plates, the impact of a projectile traveling at high speed flattens the spring without affording sufficient protection to the armor. To overcome this weakness, I provide auxiliary springs secured to the base but of less

length than the primary and secondary springs and therefore normally out of contact with the impact plates. Where, as is preferable, the primary springs are of the helical type, said auxiliary springs may be mounted within the primary springs. Where such auxiliary springs are provided the efficiency of the armor is improved because the longer primary and secondary springs receive the initial impact of the projectile and by their relatively rapid compression neutralize the penetrating effect, while, as the impact surface of the armor moves inwardly toward the base, the auxiliary springs are in turn compressed, halting the projectile and causing it to rebound away from the armor.

While I prefer to form the outer skin or impact surface of relatively small plates flexibly linked together, I may substitute therefor a chain mat.

In the accompanying drawings, which are intended to illustrate the principles of my invention but not to limit the scope of the same to the construction shown, Figure 1 is a broken edge view of my armor; Fig. 2 is a cross section of the same; Fig. 3 is a rear face view with the base omitted for the sake of clearness; Fig. 4 is a view similar to Fig. 1 but showing a modification; Fig. 5 is a view similar to Fig. 3 but showing the said modification; Fig. 6 is an exterior face view of the chain mat impact surface; Fig. 7 is a broken edge view of my improved armor provided with said chain mat; Fig. 8 is a broken side view showing a means of anchoring the primary or other springs to the base, and Fig. 9 is a similar view showing a method of anchoring the primary and secondary springs to both the base and to the impact surface.

The following is a detailed description of the drawing, reference being first had to Figs. 1, 2 and 3. A represents the base or backing plate of the armor structure. Said base may be a steel plate attached to the hull of a ship, the parts of a vehicle, the wall of a fort or other structure or the clothing or body of a human being or animal, or the hull of a ship or the wall of a structure may itself be used as the base A. The base A is of course of the proper shape and contour to fit the surface or object to which it is applied. I have shown, for the sake of illustration, the base A as rigid but it is evident that the same may be flexible or elastic, if

desired. Where the armor is to be applied to an irregular surface, flexibility in the base would of course be advantageous. B represents a plurality of steel plates, preferably rectangular in contour and flexibly connected together at their abutting edges, as by the links 1. The thickness or gage of the plates varies in accordance with the character of the projectiles to be repelled but said plates should be of such thickness and hardness that the supporting springs, to be described, will be compressed before the plates are penetrated, broken or distorted. The facial area of said plates also varies. Thus where projectiles of the largest caliber are to be repelled, said plates may be, say, a foot square, while in the case of body armor, intended to repel machine gun and rifle fire plates an inch square will suffice. C represents strong steel springs, preferably of the helical type whose bases are anchored to the outer face of the base A and whose outer ends are anchored to the inner surface of the plates B. I prefer to provide one of said springs C, which I term "primary" springs for each of the plates B, the diameter of the spring being slightly less than the axis of the plate. The springs C are preferably set as close together as possible. Any convenient method of anchoring the springs firmly in place may be used. Thus in Fig. 8, I show a metal strap or cleat 2 bearing inwardly on the lowermost cycle of a series of springs and riveted or otherwise secured to the base A between the springs. In Fig. 9, I show clips 3 riveted or otherwise secured to the inner face of an impact plate B and turned down over the end cycle of the spring. Where a plurality of springs are to be anchored to the same plate, as for instance the base A, I prefer to employ the cleat 2, but where an individual spring is to be anchored independently of adjacent springs, I prefer the clips 3. The means of anchorage are largely omitted in Figs. 1, 2 and 3, to avoid confusion. D represents the "secondary" springs, preferably of less diameter than the primary springs and interposed between the latter, as it were, in the corner formed by four adjacent primary springs. At their bases said secondary springs are anchored to the base A, while at their outer ends, each of said springs is anchored to each of the four plates B whose corners join. Thus each plate B is bodily supported by its primary spring C, while its corners in common with the corners of the adjacent plates are supported by the secondary springs D. As shown in Figs. 2 and 3, mounted on and anchored to the base A within the primary springs C are auxiliary helical springs E which are of somewhat less length than the primary springs and therefore are not engaged and compressed by the plates B until said primary springs

are partially collapsed. I prefer also to provide still smaller and shorter conical springs F anchored to the base A, within the springs E, which are engaged and compressed by the plates B subsequent to the engagement 70 of the springs E. When a projectile strikes a plate B, its primary spring C and the adjacent secondary springs D, together with the other neighboring springs both primary and secondary to a less degree, are compressed, thus preventing penetration and lessening the speed of the projectile, and subsequently the auxiliary springs E or F and F are compressed, as the plate B is forced inwardly toward the base A, thus 75 neutralizing the impact and eventually, by the expansion of the springs, throwing the projectile off from the armor. It is evident that if the plate is not broken or penetrated at the moment of impact, penetration will 80 not occur, as the yielding of the springs will diminish the force of the blow and eventually halt the projectile and throw it off. In case the impact is delivered at the edge or corner of the plate, the secondary springs 85 prevent the breaking of the connecting links 1 and aid in the distribution of the force of the blow over a large area of the outer skin or impact surface.

In Figs. 4 and 5, I have shown the secondary springs as zigzag plate springs D' on four sides of the primary spring C, and anchored by clips 3 to the base A and to plate B along its four sides. It is evident that the function and operation of the 90 springs D' is similar to that of the springs D. Where the armor is vertically placed, I may use the zigzag secondary springs, but I prefer the helical secondary springs for armor otherwise placed.

In Figs. 6 and 7, I show a chain mat B' substituted as an outer skin for the linked together plates B. The springs C and D are anchored to the chain mat by means of rings 4 or other convenient fasteners, the 95 secondary springs D filling in the corners between the primary springs C. The length and strength or resistance of the springs, of course, vary with the character of projection to be afforded. Where large 100 and heavy projectiles are to be repelled the springs are made larger and heavier while much shorter and weaker springs are required to repel small arms fire.

Where the armor is to be used under 105 water, the material is rendered rust proof in any well known manner.

It is evident from the foregoing that my improved armor is much lighter and less expensive than the solid, thick armor now 110 in use for vessels and vehicles of war and its lightness enables it to be used for the protection of persons and animals employed in the zone of hostility while the use 115 of solid armor of effective character for 120

the protection of persons and animals is now impractical owing to its excessive weight. Where explosive projectiles are used against my armor, the shell is either 5 repelled from the armor before it explodes or the force of the explosion is neutralized by the armor and the missiles scattered by the exploding shell are easily repelled.

What I desire to claim is:—

10 1. In resilient protective armor, the combination of a base, a flexible outer skin, primary springs at regular intervals interposed between said base and said outer skin, and secondary springs of less diameter interposed between said base and said outer skin and located in the corners formed by four adjacent primary springs, as and for the purpose set forth.

20 2. In resilient protective armor, the combination of a base, a flexible outer skin formed of metallic elements loosely connected together, primary springs of relatively large diameter interposed between said base and outer skin and located close 25 together, each adjacent four of said springs thus containing between them a substantially square vacant space, and secondary springs of less diameter interposed between said base and said outer skin and occupying said vacant spaces, substantially as and for the purpose described.

30 3. In resilient protective armor, the combination of a base, an outer skin composed of metal plates flexibly connected together 35 at their abutting edges, primary springs interposed between said base and each of said plates, and secondary springs interposed between said base and the edges of said plates, as and for the purpose described.

40 4. In resilient protective armor, the combination of a base, an outer skin composed of metal plates flexibly connected together at their abutting edges, primary springs interposed between said base and each of said

45 plates, and secondary springs interposed between said base and the abutting edges of adjacent plates, as and for the purpose described.

5. In resilient protective armor, the combination of a base, an outer skin composed 50 of rectangular metal plates flexibly connected together at their abutting edges, primary springs interposed between said base and each of said plates, and a secondary spring interposed between said base and 55 each four abutting corners of adjacent plates, as and for the purpose set forth.

6. In resilient protective armor, the combination of a base, a flexible outer skin, springs interposed between said base and 60 said outer skin and anchored to both of the same, and auxiliary springs anchored to said base and of less length than said first named springs whereby said auxiliary springs are out of contact with said outer 65 skin except when said first named springs are partially compressed, substantially as and for the purpose described.

7. In resilient protective armor, the combination of a base, a flexible outer skin, 70 helical springs interposed between said base and said outer skin and anchored to both of the same, and shorter auxiliary springs within said first named springs and anchored to said base, whereby said auxiliary springs are out of contact with said outer skin except when said first named springs are partially compressed, substantially as and for the purpose described.

8. In resilient protective armor, the combination of a base, an outer skin composed of metal plates flexibly connected together at their abutting edges, primary helical springs interposed between said base and each of said plates and anchored to both of 85 the same, shorter auxiliary springs within said primary springs and anchored to said base, and secondary springs interposed between said base and the abutting edges of adjacent plates and anchored at both ends, 90 substantially as and for the purpose described.

Signed at Pittsburgh, Pa., this 8th day of January, 1916.

SALVADOR MONTES ALMENGUAL.
